UNITED STATES PATENT OFFICE

ARDE BULOVA, OF NEW YORK, N. Y., ASSIGNOR TO BULOVA WATCH COMPANY, INC.,
OF NEW YORK, N. Y., A CORPORATION OF NEW YORK

DESIGN FOR A DIAL FOR WATCHES AND CLOCKS

Application filed June 25, 1931. Serial No. 40,324. Term of patent 3½ years

To all whom it may concern:

Be it known that I ARDE BULOVA, a citizen of the United States, residing at New York City, county and State of New York, have invented a new, original, and ornamental Design for a Dial for Watches and Clocks, of which the following is a specification, reference being had to the accompanying drawing, forming part thereof.

The figure is a front view of a dial for watches and clocks showing my new design.

The hatching shown on the drawing represents a mirrored surface.

I claim:

The ornamental design for a dial for watches and clocks, as shown and described.

ARDE BULOVA.
